UNITED STATES PATENT OFFICE.

HUGH EDWARD HOUSTON, OF WICHITA FALLS, TEXAS.

SPRINKLER.

1,152,636.

Specification of Letters Patent.

Patented Sept. 7, 1915.

Application filed July 21, 1914. Serial No. 852,305.

To all whom it may concern:

Be it known that I, HUGH EDWARD HOU-
STON, a citizen of the United States, and a
resident of Wichita Falls, in the county of
5 Wichita and State of Texas, have invented a
new and Improved Sprinkler, of which the
following is a full, clear, and exact descrip-
tion.

My invention relates to devices employed
10 more particularly for sprinkling lawns; and
the object thereof is to provide a simple,
convenient and inexpensive device which
can be easily and quickly attached to a
garden hose, and which device has simple
15 means for placing the same into operative
or into inoperative position.

With the above and other objects in view,
the nature of which will more fully appear
as the description proceeds, the invention
20 consists in the novel construction, combina-
tion and arrangement of parts as herein
fully described, illustrated and claimed.

In the accompanying drawings, forming
25 part of the application, similar characters
of reference indicate corresponding parts in
all the views, and Figure 1 is a vertical cross
section of a garden hose provided with an
embodiment of my invention; Fig. 2 is a
30 plan view of a section of a garden hose pro-
vided with my invention; Fig. 3 is a plan
view of the binding flange; and Fig. 4 is a
plan view of the sections forming the nipple
of the device.

Referring to the drawings, 5 represents a
35 garden hose in which a suitable aperture 6
is formed, the diameter of said aperture 6
being smaller than the outer diameter of
the nipple sections 7 so that when said nip-
ple sections are forced into the aperture the
40 same will maintain the sections against one
another. The lower ends of the nipple sec-
tions 7 are provided with lateral flange por-
tions 8 which form a part of a cylindrical
surface adapted to conform with the inner
45 surface of the hose, as best seen in Fig. 1.
Fitting over the outwardly projecting ends
of the nipple sections 7 is a retaining flange
or washer 9, said flange being similarly cy-
lindrically shaped so that it will conform to
50 the outer surface of the hose 5. The flange
is provided with an annular central collar
10 fitting snugly about the nipple sections 7.

The nipple sections 7 adjacent the collar
10 are provided with a continuous thread 11
55 engaged by the interiorly threaded portion
12 of a sprinkler head 13. The portion of

the head above the threaded portion 12 is
preferably semi-spherical and provided
with a large number of perforations 14.
The sprinkler head 13 when screwed on to 60
the nipple sections 7 comes in engagement
with the collar 10 of the retaining flange 9,
thus causing a drawing action on the nipple
sections and thereby firmly securing the nip-
ple sections to the hose 5. 65

The sprinkler head 13 is provided with an
outer lateral flange 15 adjacent the threaded
portion 12 thereof and also with an exterior
thread 16 adjacent said flange 15. A cap 17
can be secured on to the thread 16 of the 70
sprinkler head 13 with the flange 18 of the
cap coming in contact with the flange 15 of
the head, whereby said sprinkler head is
placed into inoperative position, as indi-
cated in dotted lines in Fig. 1. Therefore, 75
to allow water to escape through the perfo-
rations 14 of the sprinkler head the only
thing necessary is the removal of the cap 17.
To shut off the water, the cap is placed on
80 to the head as stated. To prevent the mis-
placement of the cap 17, the same is se-
cured to the retaining flange 9 by a suitable
flexible member 19.

From the foregoing description, taken in
connection with the accompanying draw-
ings, the advantage of the construction and
operation of the device shown will be
readily understood by those skilled in the
art to which the invention pertains; and
while I have described the principle of oper-
ation, together with the device which I now
90 consider to be the best embodiment thereof,
I desire to have it understood that the de-
vice shown is merely illustrative and that
such changes may be made when desired as
95 are within the scope of the appended claims.

Having thus described my invention, I
claim as new and desire to secure by Letters
Patent:

1. In a device of the class described, nipple
sections having a flange portion at one end
adapted to fit the interior surface of a hose
and a threaded portion at the other end, a
retaining flange adapted to fit the nipple
sections and fit the outer surface of the hose,
100 a sprinkler head adapted to engage the
threaded portion of said nipple sections and
force said retaining flange toward the flange
portion of said nipple sections, and a
threaded cap for said sprinkler head re- 105
movable therefrom.

2. In a device of the class described, a

nipple having a flange portion and a threaded portion, said flange portion being adapted to fit the interior surface of a hose, a retaining flange associated with said nipple and adapted to fit the exterior surface of the hose, a sprinkler head adapted to engage the threaded portion of the nipple and force said retaining flange toward the flange portion of the nipple, and a threaded cap for said sprinkler head removable therefrom.

3. In a device of the class described, a nipple formed of longitudinal sections, said sections having flange portions at one end, said flange portions forming part of a cylindrical surface adapted to contact with the interior surface of a hose, said nipple sections having the other end threaded, a retaining flange forming part of a cylindrical surface adapted to fit the exterior surface

of a hose, said retaining flange having an annular collar adapted to receive the nipple sections, a sprinkler head adapted to engage the threaded parts of said nipple sections and said collar of said retaining flange, whereby the retaining flange is forced toward the flanged part of the nipple sections, and a threaded cap for said sprinkler head removable therefrom whereby the same can be placed into operative or into inoperative position.

30 In testimony whereof I have signed my name to this specification in the presence of two subscribing witnesses.

H. EDWARD HOUSTON.
